UNITED STATES PATENT OFFICE.

FRANK E. SAGENDORPH, 2d, AND BERNHARD J. STEINBERG, OF PHILADELPHIA, PENNSYLVANIA, ASSIGNORS TO AMERICAN METAL STAMPING COMPANY, OF PHILADELPHIA, PENNSYLVANIA, A CORPORATION OF DELAWARE.

SEPARATOR-FOLLOWER FOR PACKAGES, BOXES, OR THE LIKE.

SPECIFICATION forming part of Letters Patent No. 769,025, dated August 30, 1904.

Application filed February 3, 1904. Serial No. 191,881. (No model.)

To all whom it may concern:

Be it known that we, FRANK E. SAGENDORPH, 2d, and BERNHARD J. STEINBERG, citizens of the United States, and residents of Philadelphia, Pennsylvania, have invented certain Improvements in Separator-Followers for Packages, Boxes, or the Like, of which the following is a specification.

Our invention relates to certain improvements in devices for separating from each other objects which were they allowed to come into contact would probably injure themselves; and it consists more particularly in a novel form of separator for keeping apart reflectors.

The object of the invention is to provide a separator for introduction between the individual ones of a series of reflectors packed in a crate or box for preventing motion of said reflectors as well as possible contact of said reflectors one with the other.

This object we attain as hereinafter set forth, reference being had to the accompanying drawings, in which—

Figure 1 is a plan view of our improved separator. Fig. 2 is a side elevation of the separator shown in Fig. 1. Fig. 3 is a sectional elevation of a box, showing a number of reflectors in position therein and separators of our novel construction placed between them; and Figs. 4 and 5 are sectional elevations of special forms of our improved separator.

In shipping reflectors of the type particularly described and claimed in United States Letters Patent No. 744,692, dated November 17, 1903, we have found it absolutely necessary to provide some simple and inexpensive means for preventing motion of the reflectors; otherwise the enamel with which they are coated becomes scratched and otherwise injured. We have employed for this purpose barrels containing excelsior or other packing material, but have found that in addition to a relatively high cost such packing material invariably collected and retained moisture,

which caused discoloration and other injury to the enamel and paint of the reflectors. Again, the reflectors were packed in boxes and held in place by cleats; but this was not only found to be expensive, but also invariably permitted more or less motion of the reflectors, so that, as before, injury was done to the enamel or paint.

In order to overcome the above-mentioned objections, we have devised the separator shown in the above drawings, in which A and A' are two pieces of wood held together in the same plane and at right angles to one another, as shown in Fig. 1. Upon each of these pieces we nail or otherwise permanently fix two cleats *a*, whose inner or adjacent faces are equidistant from a point which is the center of a circle tangent to the ends of the pieces A and A'. Upon the face of said cross-pieces opposite to that having cleats *a* we fasten a flat piece of felt, fabric, or other soft material, preferably in the position shown, and in utilizing the separators we provide a box (indicated at B) in which the reflectors and separators are packed. On the bottom of this we place a reflector with a separator under it, if desired, as indicated diagrammatically at *b*. This reflector is conical in shape, being made with a collar *b'* at its central portion and so assembled that the lower edge of said collar is preferably in the same plane as the outer edge of the reflector, although this is not necessarily the case. In packing said reflectors, therefore, our improved form of separator is placed with the felt or paper *a'* in contact with or resting upon the top edge of the collar *b*, the cleats *a* being uppermost. The box B is of such size that the wooden pieces A and A' fit in it tightly, it being understood that the reflectors themselves are circular in form.

When a reflector is placed upon a separator, it will be seen that the collar *b'* fits between the cleats *a*, so as to be held from motion thereby, while the outer edge or rim of said reflector rests upon the outer extremities of

the pieces A and A'. A second separator is then placed upon the top of the reflector, and so on until the box is filled. If desired, the pieces A and A' may be nailed to the sides of 5 the box B; but this is not necessary.

If the collar b' should not extend to the plane of the outer edge of the reflector, but should be of a length similar to that in Fig. 5, we may, if desired, provide cleats a², having 10 notched or offset portions to accommodate the collar and support and hold the same. It is obvious that the cleats may be outside of the collar, or they may be placed as illustrated at a³ in Fig. 4, so as to contact with the inner 15 surface of the collar.

From the above description and illustrations it will be seen that we have provided an inexpensive and simple device for preventing injury to reflectors hitherto resulting in considerable loss, in addition to which it will be 20 noted that the labor required, both for packing and unpacking the reflectors, is considerably lessened by the use of the device in question.

25 We claim as our invention—

1. A separator including a plurality of cross-arms, means adjacent to the center of said arms for retaining a collar in position and a sheet of relatively soft material on the 30 face of said arms opposite to that having said retaining means, substantially as described.

2. A separator including a plurality of arms united to each other, cleats attached to the arms adjacent to their point of junction with each other and a sheet of relatively soft material on the face of said arms opposite to that having the cleats, substantially as described. 35

3. A separator including a plurality of arms connected together at an angle to each other and of substantially equal lengths from their 40 point of junction, said arms lying in the same plane and having cleats on one face, said cleats being placed adjacent to said point of junction and each having a portion for engaging the collar supported by the separator, sub- 45 substantially as described.

4. A separator consisting of a pair of arms lying in the same plane and connected to each other substantially at right angles, said arms each having upon it a pair of cleats adjacent to the center of a circle tangent to the ends of the arms, with a sheet of relatively soft material on the face of said arms opposite to that having the cleats, substantially as described. 50

In testimony whereof we have signed our 55 names to this specification in the presence of two subscribing witnesses.

FRANK E. SAGENDORPH, 2d.
BERNHARD J. STEINBERG.
